METALLIC ATTACHMENT

Harry Sheer, Brooklyn, N. Y.

Application December 24, 1935, Serial No. 55,973

1 Claim. (Cl. 24—226)

This invention relates to connection devices for attachment to various articles and more particularly to those formed of plastic material such as clasps, buckles and the like and especially for use with such articles formed of catalin and celluloid.

One of the principal objects of the invention is to provide attachments for use with such articles having improved means for securing them to the same. Another object is to provide a clasp member which has a base portion of suitable material, and attachments secured thereto, one of which is adapted to have one end of a belt permanently attached to it, and another being a connection member, such as one having a hook or one having an eye or slot to be engaged by a hook, or other suitable devices adapted to engage for connecting the ends of a belt, said attachments being provided with my improved means for attaching them to the base portion. A further object is to provide a metallic attachment to which a piece of plastic material such as celluloid or catalin is secured and which can be applied to a clasp or buckle base by cementing or pasting it thereto or other suitable manner.

The means I prefer to employ for accomplishing the above objects, together with other advantageous and novel features of my invention, are illustrated in the drawing accompanying and forming part of this specification, and in which—

Figure 1 is a rear elevation of a clasp employing my improved attachments.

Fig. 2 is a side elevation of the same.

Fig. 3 is a front elevation of the same.

Fig. 4 is a plan of the same.

Fig. 5 is a side elevation of one form of my improved attachments.

Fig. 6 is a rear elevation of the same.

Fig. 7 is a section of the same taken on the line 7—7 of Fig. 6.

Fig. 8 is a side elevation of another form of my attachments.

Fig. 9 is a plan of the rear of the same.

Fig. 10 is an elevation as seen from the right of Fig. 9.

Fig. 11 is a side elevation of another form of my attachments.

Fig. 12 is a plan of the rear thereof.

Fig. 13 is an elevation as seen from the right of Fig. 11.

Fig. 14 is a rear elevation of another form of my attachments, and

Fig. 15 is a side elevation of the same.

Referring to Figs. 1 to 4 inclusive of the drawing, the numeral 2 indicates the base portion of an article to be supplied with attachments, in this instance being a clasp for a belt, 3 indicates one of the attachments, and 4 indicates another

of the attachments. The attachment 3 is illustrated on a larger scale in Figs. 5, 6, and 7, and consists of a raised elongated portion or bar 5, end portions 6, and juncture portions 7 joined to the end portions. The juncture portions 7 have perforations 8 and attached to the edges of the perforations 8 are prongs or points 9.

Attached to the portions 6 are parts 10, in this case said parts being thin rectangular pieces of plastic material such as catalin or celluloid, which parts are held against the faces 11 of the juncture portions 7, the prongs or points 9 being forced through or into the parts 10 and their ends forced outwardly so as to be well embedded in said parts 10, and to hold the same securely against the juncture portions 7. The portions 5 are attached to the parts 10 and the latter cut to size all in one operation of a press. The attachments 3 are adapted to have flexible material such as a belt attached to them as by looping it around said bars 5.

Figs. 8, 9, and 10 illustrate the attachment 4, which has a hook 14 and a body portion 15 provided with perforations 8 and prongs 9. There are parts 10 of plastic material held against the juncture faces 16 of the body portions 15 by means of the clinched prongs 9 embedded in or forced through them.

Figs. 11, 12, and 13 show another form of attachment which is indicated by 17 and consists of a body portion 18 and a front extension 19 having a slot 20 suitable for engaging with a hook. The body portion has perforations 8 and prongs 9, and there are parts 10 of plastic material secured by the prongs 9 embedded in them, to the body portion 18.

Figs. 14 and 15 show a modified form of the attachment 3 and in said figures 21 indicates the elongated bar, 22 the bent end parts, and 23 the juncture portions. To the latter are applied the parts 10 of plastic material by the prongs 9 embedded in them.

What I claim is:—

In a clasp comprising a base portion made of celluloid and a coupling element secured to one of the ends of said base portion, means adhered to said base portion for anchoring the loop of a belt to said base portion, said means comprising a longitudinal flat metal strip terminating at each of its ends in a flat tab offset from and parallel to said main body member; a celluloid facing covering the outside surface of each of said tabs and adhered to said base portion; and a plurality of prongs struck out of each of said tabs and extending into the celluloid facing immediately adjacent thereto for attaching said celluloid facings to said tabs.

HARRY SHEER.
